LEO L. LEWIS, OF PLAINFIELD, NEW JERSEY, ASSIGNOR TO CARRIER ENGINEERING CORPORATION, OF NEWARK, NEW JERSEY

APPARATUS FOR CONDITIONING INCLOSURES

Application filed February 23, 1928. Serial No. 256,258.

Ventilating and air conditioning systems are commonly employed at the present time for producing in buildings or inclosures, comfortable and healthful atmospheric conditions or temperature and humidity conditions which are specially suited to the particular purposes for which the inclosures may be used. Such systems are extensively used, for example, for ventilating and conditioning theaters, auditoriums or other places where people congregate in varying numbers, and are particularly desirable for cooling them in hot weather. The effect produced by the body heat and moisture emanating from the people upon the temperature and humidity in the inclosure depends very largely upon the number of people. It is desirable to maintain substantially the same comfortable conditions in the inclosure whenever it is occupied, irrespective of the number of people therein, but since the number varies widely at different times, and often in a very short space of time, this seriously complicates the problem of maintaining at all times the desired atmospheric conditions. The system must be designed to give the proper conditions when the inclosure is filled or overcrowded, and this frequently results in overcooling or undesirable conditions when the inclosure is only sparsely occupied. The air conditioning equipment for a high class theater or similar place usually includes a refrigerating machine for dehumidifying the air supplied to the inclosure so as to keep the relative humidity in the inclosure down within the desired limits and to cool the inclosure in warm weather. In moving picture theaters and analogous places of assembly which operate more or less continuously throughout a considerable portion of the day and night, it is necessary to run the refrigerating machine from the time it is started, which may be ten or eleven A. M., noon or two P. M., depending upon the hour of opening, until the theater closes at night, which may be eleven P. M. or later. Regardless of what time the theater may open, it is almost invariably true that from an hour to an hour and one-half is required to build

up the audience much in excess of twenty to twenty-five percent of the theater's capacity. On the other hand, the crowds begin to thin out during the afternoon, say around four o'clock, and often by five o'clock in the case 55 of the continuous show, the house is probably depleted to only about ten percent of its capacity, and between this time and the time when the people commence to arrive for the evening performance, it is still more sparsely 60 occupied. Usually about seven o'clock the crowd begins to build up again, often reaching a tremendous overload somewhere around eight or eight thirty P. M.

As above indicated, it is necessary to run 65 the refrigerating machine during the periods when the house is practically unoccupied or only sparsely occupied as well as when it is full or nearly full. This must be done to dehumidify or keep down the dew point of 70 the conditioned air which is supplied to the inclosure, and since in conditioning systems as heretofore designed, it has been necessary in summer time to deliver some little of this conditioned air of low dew point to the in- 75 closure to cool it and keep the humidity there- down within the desired limits, the inclosure will become overcooled when it is only sparsely occupied unless heating means of some sort are available. 80

Ventilating or air conditioning systems are ordinarily equipped with one or more steam heaters for heating the conditioned air to the point necessary to give the desired temperature in the inclosure, but during warm weather no artificial heat is necessary except when the inclosure is only sparsely occupied. At other times the heat from the heaters would be objectionable. It is extremely expensive, and difficult because of the human element, to get the operator to fire up the boiler just to have steam for a short time in the morning and a short time in the afternoon, when it is necessary to avoid overcooling. It is also difficult for the owner to appreciate the necessity for operating a refrigerating machine to keep the inclosure cool and at the same time operate a steam boiler to keep it warm and to run both of these at the same time. A small gas fired boiler or a gas fired direct 95 100

heater might be used as a substitute for a coal fired boiler, but such a boiler or heater would involve an additional installation expense, and they are also quite expensive to operate.

5 One or more electric heaters could also be used, but while they would be comparatively cheap to install, they are expensive to operate.

Everything which has been considered possible has been attempted in the way of 10 reducing the volume of dehumidified or low dew point air supplied to the inclosure with a view to preventing the objectionable overcooling, but notwithstanding such efforts, the 15 overcooling occurs to such an extent that it has been found extremely objectionable and has been a serious argument against the use of systems for cooling theaters in the summer time.

One object of my invention is to provide a 20 means which will not add materially to the cost of installation of air cooling or conditioning systems, and which will be economical and efficient in operation for preventing the overcooling of the inclosures, and which 25 will avoid the necessity for operating the usual steam boilers of the systems, or for providing and operating separate or special heaters for this purpose. Other objects of the invention are to utilize the heat resulting 30 from the condensing of the refrigerating medium in the refrigerating machine to prevent the overcooling of the inclosure; also to make provision whereby the condenser water of the refrigerating machine can be used in a 35 suitable heater, or in the heater ordinarily forming a part of the air conditioning equipment, for providing the heat necessary to prevent overcooling of the inclosure; and also to improve ventilating and air conditioning 40 methods and systems in the other respects hereinafter described and set forth in the claims.

The accompanying drawing illustrates by 45 a diagrammatic view an air conditioning system embodying my invention.

Referring to the drawing, 1 represents the inclosure to be conditioned or ventilated. This inclosure may be the auditorium of a theater, one or more rooms of a building, or 50 other inclosure. 2 is an air conditioning device in which air is dehumidified or conditioned as to its moisture content, and 3 is a fan for moving air through the air conditioner and discharging the same into the inclosure 1. The air conditioner 2 may be 55 constructed and arranged in any usual or suitable way so as to supply conditioned air to the inclosure. As shown, the air conditioner 2 is provided with an inlet 4 for fresh 60 air and with a passage 5 through which air may be returned from the inclosure to the intake of the air conditioner so that either fresh air, return air from the inclosure or a mixture of any required proportions of fresh 65 and return air can be conditioned and de-

livered to the inclosure. The air is brought to the desired dew point in the air conditioner, preferably by means of water sprayed into the air by suitable nozzles 6, and a refrigerating machine is shown for cooling the spray water for this purpose. The refrigerating machine may be of any usual or suitable type, that shown being a compression refrigerating machine comprising an evaporator or cooler 7 for the spray water, a condenser 8 for the refrigerating medium and a compressor 9. The spray water for the air conditioner 2 is circulated by a pump 10 which draws the water by a pipe 11 from the bottom of the air conditioning chamber and delivers the same by a pipe 12 to the cooler 7 from which the water is delivered by a pipe 13 to the spray nozzles 6. Water is employed for condensing the refrigerating medium in the condenser 8, this water entering the condenser through a supply pipe 15 and leaving the same through a discharge pipe 16.

The apparatus as thus far described is known and may be of the construction illustrated, or of any other usual or suitable 90 construction.

In accordance with this invention, the heat resulting from the condensation of the refrigerating medium in the refrigerating machine is utilized through suitable instrumentalities for preventing overcooling in the inclosure. A suitable heater or device 20 is furnished for thus utilizing the heat of condensation.

100 In the system illustrated, this heater is located between the air conditioner 2 and the fan 3 so that the air leaving the conditioner passes through and is heated by the heater 20, but the heater could be located at any other suitable point in the system and the heater may be of any suitable construction. Ordinarily, air conditioning systems include a heater for the dehumidified or conditioned air, and the heater 20 may be such usual steam heater, or a separate heater, as may be desired. As represented in the drawing, the heater 20 is the usual steam heater and is provided with steam supply and return pipes 21 and 22. For the purpose of utilizing the condenser water from the refrigerating machine in the heater 20, two pipes 23 and 24 may be employed connecting the discharge pipe 16 of the condenser 8 respectively to the inlet and outlet fittings of the heater 20. The pipes 23 and 24 are shown equipped with valves 25 and 26 respectively, and another valve 27 is shown in the condenser discharge pipe 16 between the supply and discharge pipes 23 and 24 for the heater. If the valve 27 is closed and the two valves 25 and 26 are opened, the warm water leaving the condenser will flow through the pipe 23 to the heater 20, and after passing through the heater, will return through the pipe 24 and discharge through the pipe 16, at the other 110 115 120 125 130

side of the valve 27, to the sewer or point of discharge. By closing the two valves 25 and 26 and opening the valve 27, the water will enter the condenser through the pipe 15 and discharge through the pipe 16 to the sewer in the usual manner, without passing through the heater. Thus, the condenser water can be caused to pass through the heater or to discharge without passing through the 10 heater, as may be desired by appropriate adjustments of the valves 25, 26 and 27.

In order to adapt the same heater 20 to be either heated by steam, as in the usual systems, or to use the condenser water when heat 15 is necessary only to prevent overcooling, as above explained, the water pipes 23 and 24 may be connected as shown, with the steam supply and discharge pipes 21 and 22 of the heater, suitable three-way valves 29 and 30, 20 or valve means of any other suitable sort, being provided whereby the heater can be connected either with the steam or the water supply and discharge pipes.

In the operation of the system, the air may 25 be reduced to the required dew point in the air conditioner 2 by means of the cold spray from the refrigerating machine, the spray being controlled or the temperature in the air conditioner being otherwise regulated in any 30 of the well known ways for bringing the air in the air conditioner 2 to the desired dew point. The conditioned air is delivered from the air conditioner to the inclosure by the fan 3. When there is a sufficient number of 35 people or other source of heat in the inclosure, it is not necessary in warm weather to operate the heater 20 to heat the conditioned air which is delivered to the inclosure, but the conditions in the inclosure may be controlled to maintain the desired temperature 40 and relative humidity therein in the usual way, as for instance, by properly regulating the volume of air withdrawn from the inclosure and the volume and dew point of the 45 conditioned air delivered to the inclosure, which conditioned air may be either outside fresh air, return air from the inclosure, or appropriately regulated mixtures of the outside and return air. When, however, there 50 are so few people in the inclosure that the minimum amount of air of low dew point supplied thereto from the air conditioner 2 will overcool the inclosure, then the condenser water is caused to flow through the heater 55 20 by appropriate adjustments of the controlling valves of the water supply and discharge pipes, as above explained, and the heat from the condenser water will raise the temperature of the conditioned air supplied 60 to the inclosure, sufficiently to give the desired temperature and relative humidity in the inclosure.

The condenser water, which, if properly controlled, may be heated as high as 100 degrees, is capable of supplying just about the

requisite amount of heat to raise the conditioned air to the temperature necessary to keep the relative humidity in the inclosure down to the desired maximum and prevent overcooling of the inclosure. The temperature of the condenser water leaving the condenser can be raised by reducing its volume, and reduced by increasing its volume, so that it is possible by appropriate regulation of the volume of condenser water to obtain the 70 temperature thereof necessary for reheating the conditioned air. The required temperature of the outgoing condenser water can be obtained regardless of its incoming temperature. It is simply a matter of appropriate regulation of the volume of water passing 75 through the condenser.

I claim as my invention:

1. In a system for conditioning the atmosphere of an inclosure, the combination of air 85 conditioning apparatus, means for conveying air through said apparatus and to said inclosure, means including a refrigerating device for lowering the dewpoint of the air passing through said apparatus and including a condenser, means for circulating a fluid through said condenser, a heater for heating air leaving said apparatus and moving to said inclosure, and means connected to said heater for supplying additional heat thereto, whereby said heater may be connected selectively 90 either to said last means or in series with the outgoing side of said condenser.

2. In a system for conditioning the atmosphere of an inclosure, means for supplying air 100 to said inclosure, means including a refrigerating device for lowering the dewpoint of said air which is supplied to said inclosure, said device having a condenser, means for passing a cooling fluid through said condenser and including a pair of pipes for conveying said fluid to and from said condenser, a heater having a pipe for heating the said air supplied to said inclosure after its dewpoint 105 has been lowered and before its admission to said inclosure, means including a connection from said heater to said pipe conveying fluid from said condenser for diverting selectively any desired amount of fluid leaving 110 said condenser through the pipe of said heater, and means also connected to said heater pipe for admitting thereto a separate heating fluid whenever the heat from said condenser fluid is insufficient.

3. In a system for conditioning the atmosphere of an inclosure, the combination of an air conditioning chamber, means for circulating air through said chamber to said inclosure, a heater for heating the air leaving said chamber and entering said inclosure, means including a refrigerating device for lowering the dewpoint of the air as it passes through said chamber, said device having a condenser, means for passing a cooling fluid 120 through said condenser continuously and in 125 through said condenser continuously and in 130

- cluding a pair of pipes for conveying fluid to and from said condenser, the pipe carrying fluid from said condenser having a shut-off valve therein, connections between said outgoing fluid pipe, at opposite sides of said valve, and the opposite ends of said heater, whereby when said valve is closed, the fluid leaving said condenser will be diverted through said heater, and when open said heater will be unaffected by said condenser, and connections directly to said heater, for supplying thereto a separate heating fluid whenever operation of said heater separately from said condenser is desired.
- 15 4. In a system for conditioning the atmosphere of an inclosure, the combination of an air conditioning chamber, means for circulating air through said chamber to said inclosure, a heater for heating the air leaving said chamber and entering said inclosure, means including a refrigerating device for lowering the dewpoint of the air as it passes through said chamber, said device having a condenser means for passing a cooling fluid through said condenser continuously and including a pair of pipes for conveying liquid to and from said condenser, the pipe carrying fluid from said condenser having a shut-off valve therein, connections between said outgoing fluid pipe, at opposite sides of said valve, and the opposite ends of said heater, whereby when said valve is closed, the fluid leaving said condenser will be diverted through said heater, and when open said heater will be unaffected by said condenser, valves in said connections to said heater, and pipes to said connections at points between said heater and said valves for supplying heat to the heater separately from the condenser.
